COMBINED SEAT AND EASEL

Raymond E. Cote, Menomonee, Wis.

Application January 16, 1956, Serial No. 39,770

Term of patent 14 years

(Cl. D15—8)

FIG. 1

FIG. 2

FIG. 3

FIG. 4

Fig. 1 is a plan view of a combined seat and easel, showing my new design;

Fig. 2 is a right end view of the design shown in Fig. 1;

Fig. 3 is a side view of the design shown in Fig. 1; and

Fig. 4 is a front perspective view of the design shown in Fig. 1.

I claim:

The ornamental design for a combined seat and easel, as shown.
